US00D953304S

(12) **United States Design Patent** (10) **Patent No.:** **US D953,304 S**
Huang (45) **Date of Patent:** **** May 31, 2022**

(54) **WIRELESS MICROPHONE**

(71) Applicant: **SHENZHEN LYNCA
PHOTOGRAPHIC EQUIPMENT
CO., LTD**, Shenzhen (CN)

(72) Inventor: **Xita Huang**, Shenzhen (CN)

(**) Term: **15 Years**

(21) Appl. No.: **29/767,993**

(22) Filed: **Jan. 27, 2021**

(30) **Foreign Application Priority Data**

Aug. 12, 2020 (CN) 202030457961.1

(51) **LOC (13) Cl.** **14-01**

(52) **U.S. Cl.**

USPC **D14/225**

Primary Examiner — Paula Allen Greene

(57) **CLAIM**

The ornamental design for a wireless microphone, as shown and described.

DESCRIPTION

FIG. 1 is a first perspective view of a wireless microphone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the wireless microphone in which the design is embodied that form no part of the claimed design.

1 Claim, 8 Drawing Sheets
